(57) **CLAIM**

The ornamental design for a floorboard timing cover and exhaust guard for a motorcycle, as shown and described.

DESCRIPTION

FIG. 1 is a front view of the present invention;

FIG. 2 is a back view thereof;

FIG. 3 is a top view thereof;

FIG. 4 is a bottom view thereof;

FIG. 5 is a right end view thereof;

FIG. 6 is a left end view thereof; and,

FIG. 7 is a perspective view of the present invention on a reduced scale in use on a motorcycle.

The material shown in dotted line forms the environment of the use of the present design and is not claimed herein as a part thereof.
